(57) **CLAIM**

The ornamental design for a fluorescent yellow colored plastic net structure, as shown and described.

DESCRIPTION

The patent or application file contains at least one drawing executed in color. Copies of this patent or patent application publication with color drawing(s) will be provided by the Office upon request and payment of the necessary fee.

FIG. 1 is an enlarged fragmented front view of a fluorescent yellow colored plastic net structure showing my new design in a flat configuration; and,

FIG. 2 is a perspective view of the fluorescent yellow colored plastic net structure of FIG. 1 in a rolled-up configuration. Color, namely fluorescent yellow color, is a feature of the design as noted in the informal drawings comprising the color photographs that were submitted with the application.
